UNITED STATES PATENT OFFICE.

WILLIAM J. HOGUE, OF KANSAS CITY, MISSOURI.

OIL-WELL-CLEANING APPLIANCE.

1,293,777.

Specification of Letters Patent. Patented Feb. 11, 1919.

Application filed November 4, 1918. Serial No. 261,088.

To all whom it may concern:

Be it known that I, WILLIAM J. HOGUE, a citizen of the United States, residing at Kansas City, in the county of Jackson and State of Missouri, have invented certain new and useful Improvements in Oil-Well-Cleaning Appliances, of which the following is a specification.

This invention relates to oil well cleaning appliances of that class by which the interior of the casing of the well is cleaned by scraping action and the scrapings are forced upward through the casing by the circulation of a liquid therethrough, and my object is to produce an efficient appliance in which reciprocatory movement of a plunger member shall effect both oscillatory action of a series of scraper blades on the interior of the casing and pumping action of a cleaning or flushing liquid up through the casing.

A further object is to provide means self-adjustable to the interior diameter of the casing, for guarding against rotary action of the plunger member while being reciprocated; scraper blades which adapt themselves to slight changes or irregularities in the interior diameter of the casing. A still further object is to provide means for effecting appreciable adjustment of the scraper blades for the accommodation of casing of considerable variation in diameter, without limiting the capacity of the scraper blades for accommodating slight changes or irregularities in the interior diameter of the casing.

With these general objects in view the invention consists in certain novel and useful features of construction and combinations of parts as hereinafter described and claimed; and in order that it may be fully understood, reference is to be had to the accompanying drawing, in which:

Figure 1, is a view partly in side elevation and partly in central vertical section, of an oil well cleaning appliance embodying the invention.

Fig. 2, is a horizontal section on the line II-II of Fig. 1.

Fig. 3, is a horizontal section on the line III-III of Fig. 1.

Fig. 4, is an enlarged vertical section on the line IV-IV of Fig. 2.

In the said drawing, where like reference characters identify corresponding parts in all of the figures, 1 designates the casing of an oil well, the same being indicated in dot-

ted lines in Fig. 1, and in full lines in Figs. 2 and 3.

2 indicates a tube within the casing, the lower end of the tube being closed as by a plug 3 secured in place by screw bolts 4, and said plug is preferably provided with a drill bit 5 which not only has a drilling function but aids in holding the tube 2 centralized in the casing while the former is being rotated for cleaning purposes, as hereinafter explained. Just above the closure 3, the tube is provided with a series of jet openings 6, and near its upper end the tube is provided with spiral slots 7 for simultaneous engagement by a cross pin 8 rigidly secured to a reciprocatory plunger member 9, the operation of the plunger member by hand power or otherwise, effecting oscillatory rotatable action of the tube 2 through the travel of the pin 8 in the spiral slots 7. It being understood that the reciprocatory action of the plunger member corresponds to the shortest distance between the upper and lower ends of the slots 7.

The member 9 must be of length to extend to the upper end of the casing and hence will be ordinarily composed of a plurality of sections, the drawing showing only the bottom section. Because it is usually of considerable length, it is desirable to provide means for guarding against rotative action of the plunger member while being reciprocated and hence insure rotative oscillatory action of the tube 2. To guard against rotative action of the plunger member 9, the same will be provided with one or more collars 10, each being secured rigidly in place by one or more clamping bolts 11, and pivoted to and projecting from opposite sides of each collar are swing arms 12 through which extend horizontally bolts 13 forming journals for conical rollers 14 for tracking engagement with the interior wall of the casing. Secured upon each collar by the clamping bolt 11 is a clip 15, and clamped against the collar by said clip is one convolution or coil of a spring 16, the spring terminating in arms 17 which engage the swing arms 12 and exert force tending to swing said arms downward, and in order to prevent said arms from swinging downward to or below a horizontal position, angle plates 18 are secured to the collar and are provided with extensions 19 underlying the inner ends of the swing arms 12, as shown clearly in Fig. 1.

A collar 20 is secured by clamping bolts 21, firmly upon the tube 2 at any desired point, and forms an abutment or resistance point for a coiled spring 22 fitting around the tube, and secured at their upper ends to the lower convolution of said spring is a series of semi-elliptic spring scraper blades 23, the lower ends of said blades being secured firmly to the tube by means of the bolts 4, or in any other suitable manner.

10 There are four of the scraper blades shown, but the number may be increased or diminished. The blades are bowed outwardly to the desired extent and under compression 15 the spring 22 will yield, that is to say the blades upon encountering a slight irregularity on the inner face of the casing against which they are adapted to bear as shown in Fig. 1, may ride over such irregularity, the 20 blades of course re-expanding under the action of the spring 22 after passing such irregularity.

If it is desired to adapt the appliance for the operation of the blades within larger or 25 smaller casings, or the like, the collar 21 will be adjusted downward or upward respectively, the downward adjustment increasing the bow and the upward adjustment permitting of a decrease in the bowing 30 of the springs.

The reciprocation of the plunger member 9 will, as explained, turn the tube 2 first in one direction and then in the other, and hence cause the blades to shear or cut any 35 accumulation of foreign material from the interior of the casing, and in order that such material shall be forced up through the casing, a spider 24 is secured in the lower end of the plunger member and is equipped 40 with a cup valve 25 or its equivalent, adapted to open as the plunger member moves upward to permit water or the like to pass down into the lower end of the tube 2, and to close under the resistance of such 45 water or the like as the plunger is moved downward, so that the latter shall act as a piston to forcibly eject or pump water through the openings 6 and up through the casing.

50 With an appliance of this character a suitable cable may be carried to the plunger member with means whereby the plunger can be automatically raised and dropped, so that the force of gravity, may be utilized 55 in effecting the operation of the scraper blades in one direction and likewise for the discharge of water from the lower end of the tube. As means for raising and dropping the appliances are old in the art and 60 form no part of this invention, it has not been deemed necessary to illustrate or describe in detail such means.

From the above description it will be apparent that I have produced an oil well cleaning appliance which will perform its

function efficiently, and which embodies the features of advantage set forth as desirable in the statement of the object of the invention, and while I have illustrated and described the preferred construction of the appliance, it is to be understood that I reserve the right to make such changes or modifications as properly fall within the spirit and scope of the appended claims.

70

I claim:

1. An oil well cleaning appliance comprising a tube having discharge openings, a tubular reciprocatory plunger member within said tube and provided with a valve closing communication between said tubular plunger member and the underlying chamber of said tube when said member is moved downward and opening such communication when the plunger member is moved upward, one or more lower scraper blades secured to the said tube, and means whereby reciprocatory movement of the plunger member shall effect oscillatory movement of the blade carrying tube.

80

2. An oil well cleaning appliance comprising a tube having discharge openings, a

tubular reciprocatory plunger member within said tube and provided with a valve closing communication between said tubular plunger member and the underlying chamber of said tube when said member is moved downward and opening such communication when the plunger member is moved upward, one or more bowed scraper blades secured to the said tube, and means whereby reciprocatory movement of the plunger member shall effect oscillatory movement of the blade carrying tube, and means whereby reciprocating 90

95

100 movement of the plunger member shall effect oscillatory movement of the blade carrying tube, and means for preventing rotating movement of the reciprocating plunger member.

10

3. An oil well cleaning appliance comprising a tube having discharge openings, a tubular reciprocatory plunger member within said tube and provided with a valve closing communication between said tubular plunger member and the underlying chamber of said tube when said member is moved downward and opening such communication when the plunger member is moved upward, one or more bowed scraper blades secured to the said tube, and a spiral guideway and pin connection between the tube and said plunger member for causing reciprocatory movement of the latter to impart oscillatory movement to said tube.

11

4. The combination with an oil well casing, of a tube fitting within the casing, one or more scraper blades carried by the tube and exerting yielding pressure against the casing, a reciprocatory member within said tube, means for preventing the reciprocating member from turning while reciprocating, and means for causing the reciprocating member to impart oscillating movement to said tube.

11

5. The combination with an oil well casing, of a tube fitting within the casing, one or more scraper blades carried by the tube and exerting yielding pressure against the casing, a reciprocating member within said tube, means for causing the reciprocating member to oscillate the scraper blade carrying tube, swing arms carried by said reciprocating member, rollers carried by said

swing arms, and yielding means for exerting force on said swing arms to hold said rollers pressed firmly against the casing to prevent rotative movement without interfering with the reciprocating movement of the reciprocating member. ¹⁵

In testimony whereof I affix my signature.

WILLIAM J. HOGUE.
